(57) **CLAIM**

The ornamental design for a detachable putting trainer, as shown and described.

DESCRIPTION

FIG. 1 is a top left rear perspective view of the detachable putting trainer hereof shown coupled attached by hook and loop fabric to a putter and receiving a ball within a rearwardly extending loop, the putter, the ball and the hook and loop fabric being shown in dashed lines for environmental purposes only and forming no part of the claimed invention; FIG. 2 is an enlarged right rear perspective view of the detachable putting trainer hereof;

FIG. 3 is a rear elevational view thereof;

FIG. 4 is a front elevational view thereof;

FIG. 5 is a bottom plan view thereof; and,

FIG. 6 is a right side elevational view thereof, the left side elevational view being a mirror image.
